UNITED STATES PATENT OFFICE.

ALRAH B. EDWARDS, OF BIG SPRINGS, TEXAS.

DESIGN FOR A TIRE-INFLATING GAUGE.

Application filed September 10, 1926. Serial No. 19,014. Term of patent 7 years.

To all whom it may concern:

Be it known that I, ALRAH B. EDWARDS, a citizen of the United States, residing at Big Springs, in the county of Howard and State of Texas, have invented a new, original, and ornamental Design for Tire-Inflating Gauge, of which the following is a specification, reference being had to the accom-

panying drawing, forming a part thereof, in which the figure is a perspective view of the article showing my new design.

I claim:

The ornamental design for a tire inflating gauge as shown.

ALRAH B. EDWARDS.
